Fig. 7.

Fig. 8

Fig. 10

Fig. 9

FIG. 1 is a front perspective view of a pump showing our new design;

FIG. 2 is a rear perspective view thereof;

FIG. 3 is a top plan view thereof;

FIG. 4 is a rear elevational view thereof;

FIG. 5 is a side elevational view thereof;

FIG. 6 is a front elevational view thereof;

FIG. 7 is an opposite side elevational view thereof;

FIG. 8 is a top plan view of a pump casing showing a modified form of our new design;

FIG. 9 is a rear elevational view of the modified form;

FIG. 10 is a side elevational view of the modified form;

FIG. 11 is a front elevational view of the modified form; and

FIG. 12 is an opposite side elevational view of the modified form.

We claim:

The ornamental design for a pump casing, as shown and described.
